UNITED STATES PATENT OFFICE.

JOHN L. WELLER AND FRANKLIN EARL WINCHESTER, OF RICHMOND, INDIANA.

TRANSMISSION-LOCK FOR AUTOMOBILES OR THE LIKE.

1,263,826.

Specification of Letters Patent. Patented Apr. 23, 1918.

Application filed October 15, 1917. Serial No. 190,582.

To all whom it may concern:

Be it known that we, JOHN L. WELLER and FRANKLIN EARL WINCHESTER, both citizens of the United States, residing in the city of Richmond, in the county of Wayne and State of Indiana, have invented a new and useful Transmission-Lock for Automobiles or the like, of which the following is a full, clear, and comprehensive exposition and specification, the same being such as will enable others to make and use the same with exactitude.

The object of our present invention, broadly speaking, is to provide a transmission lock, for automobiles or the like, which will be strong and durable in construction, positive in action, neat and attractive in appearance, easily operated by an authorized person yet impossible to be operated by one not having the proper key, and which can be manufactured, sold, and installed at a comparatively low price.

More specifically stated our object is to provide means for locking the transmission in such manner that the machine cannot be placed in gear to be operated forward, therefore it could not be utilized until the locking means is released in an authorized manner, and also we provide means whereby the lock cannot possibly be broken off or removed, and by which it will be absolutely impossible to control the machine until the lock is released by a person having the proper key therefor.

Other objects and particular advantages of our invention will suggest themselves in the course of the following description, and that which is new will be correlated in the appended claims.

The preferred means for carrying out the principles of our invention in a practical and a mechanical manner is shown in the accompanying drawings, in which—Figure 1 is a side elevation of the control and of the cover for the transmission case, one portion being broken away in order to show the interior arrangement of the invention. Fig. 2 is a vertical cross section, as taken through our invention on the line 2—2 of Fig. 1.

Fig. 3 is a horizontal section of the lower portion of our construction, as taken on the line 3—3 of Fig. 2. Fig. 4 is a perspective view of the barrel-lock and of the bolt car-

ried thereby. Fig. 5 is detail top plan view of our invention. And Fig. 6 is plan view 55 of the key.

Similar indices denote like parts throughout the several views.

In order to make clear the construction, the application, and the operation of our invention we will now take up a description thereof, in which we will set forth the construction and operation as fully and as comprehensively as we may.

In most instances the transmission is located below the floor of the front portion of an automobile. The surface of the floor being denoted in Fig. 1 by the line A. The transmission case is denoted by the letter B. Mounted on and forming the cover of the transmission case is the control-box, which comprises a hollow base C, from around the lower edge of which extends the flange D through which the bolts E are inserted to secure the control-box in position on the transmission case B. Extending upward from the base C is the main housing F through which the control lever G operates, and in the upper portion of which it is pivoted for universal movements in the usual manner. The lower end of the lever G is adapted to move the shifting-rods H and I endwise. The said rods are slidably mounted, parallel with each other, in apertures therefor formed through the base C. 85

Each of the forks J and K is secured to one of the rods H and I, and they are so mounted as to cause them to shift the gears located in the case B when the lever G is operated in the usual manner. 90

All of said parts are of an ordinary construction and no claim is made thereto, neither is our invention to be limited to the precise construction mentioned.

The invention proper comprises a secondary housing, or projection 1, which extends out centrally from one end of the housing F, with which it is integral. It is to be understood that the housing 1, the housing F, the base C, and the flange D should be one integral casting.

Extending across into the base C, directly below the housing 1, is the aperture 2, which is round in cross section, and it intersects at right-angles the apertures in which 105 operate the rods H and I.

Numerals 3 and 4 designate balls, the same being located in the aperture 2, and they are disposed between the rods H and I. The size of said balls are such as to loosely fit in the aperture 2, and their combined diameters are only slightly less than is the distance between the rods H and I.

Formed in the opposing sides of the rods H and I are the respective segmental notches 5 and 6, whose curvature corresponds with the curvature of the balls 3 and 4 which may fit therein as shown. The location of said notches 5 and 6 are such that when the rods H and I are moved to shift the gears into neutral position the said notches will be directly opposite and in alinement with the balls 3 and 4, in which position they are indicated in Figs. 2 and 3.

Extending downward from the center of the housing 1 is the comparatively large aperture 7, which is round in cross section; and concentric therewith and continuing downward through the housing 1 is the smaller aperture 8, the same being of less diameter than the aperture 7, and it intersects the aperture 2 at a point midway of the rods H and I. By reason of the difference in the diameter of the apertures 7 and 8 there is a shoulder 9 formed at the base of the aperture 7.

Numerical 10 denotes the barrel of the lock proper, the same being of ordinary arrangement immaterial to this invention, except that it has a tumbler 11 operative therein which is adapted to be rotated by the key L which is adapted to be inserted in the key-hole 12, whereby the plunger 13, which extends through one side of the barrel, may be drawn in flush with the periphery of the barrel when said key is turned to a certain position. The barrel 10 is adapted to be inserted snugly into the aperture 7, with its upper end flush with the top of the housing 1, and with its lower end some distance above the shoulder 9. A slot 14 is formed in the housing 1 and it opens into the aperture 7, and the plunger 13 is adapted to enter thereinto as shown in Fig. 1. The said slot, or cavity, 14 may be formed before the barrel 10 is placed in position by inserting a tool through the aperture 15 which is formed opposite thereto in the wall of the housing 1, as shown in Fig. 1.

Formed in the side of the barrel 10 is a slot, or cavity 16. A screw 17 is threaded through the wall of the housing 1 with the point of the screw located in the slot 16, thereby allowing the barrel to be moved up and down within the limits of the slot 16.

60 A bolt, or stem, 18 extends down from the center of the barrel 10 and it slidably fits in the aperture 8. The lower end of the bolt 18 is pointed or rounded, as shown at 19 in Figs. 2 and 4. The lower end of the bolt 18 is adapted to enter between the balls 3

and 4, as shown in Fig. 2. Surrounding the bolt 18 is the helical spring 20, whose upper end contacts with the under face of the barrel 10 and its lower end contacts with the shoulder 9, and its tension is such as to normally press the barrel upward to its limit of movement.

The construction above described relates to locking the machine in neutral condition, however it may be locked in gear in reverse condition by simply providing the notch 21 in the rod I, which notch corresponds with the notch 6, then if the lever G be moved to reverse position the rod I will be moved to such position as will bring the notch 21 in alinement with the aperture 2, thereby providing means for the machine to be locked in such condition that it could be operated in reverse direction, that is backward.

In practice it will be apparent that if the plunger 13 be drawn in, that is flush with the barrel 10, by turning the tumbler 11 by means of the key L, that the spring 20 will then press the barrel 10 upward to the limit permitted by the slot 16, thereby removing the bolt 18 from between the balls 3 and 4, thereby allowing the balls to assume the positions in which they are shown in Fig. 3, and thereby permitting the shifting rods H 95 and I to slide forward and backward in the usual manner for shifting the gears to various speeds.

Desiring now to lock the machine one has only to move the shifting lever G to neutral position, thereby bringing the rods H and I to the positions in which they are shown in Fig. 3. Then by pressing down on the barrel 10 it is evident that the bolt 18 will be driven in between the balls 3 and 4, forcing them apart, and pressing them into the notches 5 and 6, as shown in Fig. 2. When the upper surface of the barrel 10 becomes flush with the upper surface of the housing 1 the plunger 13 will enter the slot 14, at the same time the lower end of the bolt 18 will be located between said balls, and therefore the shifting means will be absolutely secured and locked.

From the above it is evident that the rods H and I can not be moved as long as the bolt 18 remains down, as in Fig. 2, and it would therefore be impossible for one to place the machine in gear whereby it could be driven until the bolt 18 is moved upward, and evidently this could not be done until the tumbler 11 was turned to remove the plunger 13 from the aperture or slot 14, and the barrel be raised upward to its limit of movement.

It is evident that one does not have to use the key in locking the device, there being only two movements required: placing the shifting lever in neutral or reverse position, and pressing down on the barrel until 130

the plunger 13 enters the cavity 14. And then to release the device one has only to insert the key L in the key-hole 12, and then by giving a slight twist to the key the 5 plunger will be drawn in and the spring 20 will press the barrel 10 upward, thereby removing the bolt from between the balls, and therefore permitting the shifting rods to be moved in the usual manner.

10 It should be noticed that it would be absolutely impossible to break or to remove the locking means, and that the machine could not be operated unless one be provided with a particular key to fit that particular tumbler, thereby accomplishing the objects of this 15 invention.

By reason of the arrangement and the location of the parts as herein set forth it will be seen that all of the part of our invention 20 are inclosed within the metal of the transmission, and that access thereto cannot be had until the lock is in unlocked condition.

Having now fully shown and described our invention, what we claim and desire to 25 secure by Letters Patent of the United States, is—

1. In combination with the transmission of an automobile having a case and a pair of shifting rods operative parallel with each 30 other through the case, a locking mechanism formed integral with and inclosed by the case and comprising a ball for each shifting rod, said balls being normally out of the path of the respective shifting rods, a plunger 35 bolt adapted to be inserted between said balls to force them apart and into notches therefor formed in the shifting rods whereby a portion of each ball will be in the path of its respective shifting rod, and means for 40 locking the plunger bolt in position between said balls, substantially as set forth.

2. In combination with the transmission case of an automobile having a pair of rods extending parallel with each other and 45 spaced apart independent of each other, there being a segmental notch in the side of each rod which notches are directed toward each other and are located within said case, a ball adapted to fit the respective notches, 50 the balls being located in an aperture formed in the case at right angles to and extending between said rods, a bolt adapted to be pressed downward to force said balls apart and into their respective notches in the rods, 55 a lock for preventing the bolt from being moved upward from engagement with the balls, and means for automatically moving said bolt upward when the lock is released, all substantially as shown and described.

60 3. In combination with the transmission case of an automobile or the like, a pair of shifting rods operative in the case, a pair

of balls located in and operative in an aperture in the case and which is at right-angles to, extending between, and intersecting the aperture in which said rods operate, 65 said balls being adapted to contact with each other, a plunger for forcing said balls apart and into notches in the respective rods, in order to secure the rods from endwise movement when they are in neutral or reverse position, means for normally and automatically forcing said plunger from between said balls, and means for locking said plunger when it is forced downward to its limit between said 70 balls.

4. In combination with the transmission of an automobile or the like having a pair of shifting rods which are parallel with each other, a pair of balls normally out of the 80 path of said rods whereby the rods may be moved endwise, a bolt adapted to be inserted between said balls to force them apart and into the path of said rods, and means for locking said bolt against removal from between said balls, all substantially as shown and described.

5. In combination with a transmission having a control-box mounted thereon, a pair of shifting rods movable parallel with each other through the base of the control-box, and a main housing forming a part of the control-box, an auxiliary housing integral with the control-box, there being a horizontal aperture extending across at right-angles 95 and intersecting the apertures for the shifting rods and a vertical aperture extending down at right-angles to both the first mentioned aperture and the apertures for the shifting rods and intersecting the first aperture midway of the second apertures, there being notches in the shifting rods facing each other in the first mentioned aperture when the gear is in neutral or reverse position, balls located in the first mentioned aperture and located between the shifting rods, a lock-barrel located in the upper portion 100 of the vertical aperture, a bolt extending downward from said barrel and adapted to spread said balls apart when the barrel is pressed 110 downward to its limit, means for locking said barrel when it is down to its limit, and means for automatically moving the barrel upward when the lock is released, all substantially as set forth.

In testimony whereof we have hereunto subscribed our names to this specification in the presence of two subscribing witnesses.

JOHN L. WELLER.

FRANKLIN EARL WINCHESTER.
